SHOE SEWING MACHINES

Heinrich Richard Ruhr, Frankfurt am Main, Germany, assignor, by mesne assignments, to United Shoe Machinery Corporation, Flemington, N. J., a corporation of New Jersey

Application September 1, 1954, Serial No. 453,586

Claims priority, application Germany September 26, 1953

10 Claims. (Cl. 112—46)

The present invention relates to machines for sewing welts to stitchdown shoes and more particularly to improvements in devices for enabling a stitchdown welt to be severed quickly and accurately while sewing the sole margin of a stitchdown shoe in a manner to cause the final end of welt to butt and match the end of welt first attached to the shoe. In some respects the present invention is similar to that disclosed in an application for United States Letters Patent, Serial No. 418,190, filed March 23, 1954, now Patent No. 2,734,469, granted February 14, 1956, in the name of the present inventor in which devices are provided in an inseam sewing machine for enabling the final end of a Goodyear welt to be butted and matched with that end first attached to the shoe. In certain respects the invention is applicable with advantage to machines for attaching stitchdown welts to shoes otherwise than by sewing and is useful in performing auxiliary operations on the welt other than severing, butting or matching.

In the use of the devices disclosed in the prior patent a Goodyear welt shoe inseam sewing machine is provided with a supplemental welt guide in addition to the main welt guide, so arranged as to be movable along the welt running to the main welt guide and a knife mounted in the supplemental welt acts to sever the welt at a position corresponding to the end of the welt first sewed to the shoe. The position in which the supplemental welt guide in the prior application is moved is determined visually by the operator to bring the knife into predetermined relationship with the first end of the welt.

It is not possible to attach welts to stitchdown shoes with an inseam sewing machine ordinarily employed in sewing Goodyear welts. For sewing welts to stitchdown shoes an outsole stitching machine is employed. In an outsole stitching machine a stitchdown welt is led to the sewing point through a main guide formed integrally with the work support at a position where it is hidden from the view of the operator by the projecting margin of the stitchdown shoe sole. For this reason it is not possible to determine the proper position for severing a stitchdown welt visually with an acceptable degree of accuracy by the operator of an outsole stitching machine.

It is an object of the present invention to provide an outsole stitching machine with devices for enabling a stitchdown welt to be sewn uniformly and with facility equal to that enjoyed in bringing the ends of a Goodyear welt into accurately butted relationship on the inseam sewing machine of the prior application without the use of complicated actuating mechanisms.

In the machine disclosed in United States Letters Patent No. 2,388,245, granted November 6, 1945, on application of Fred Ashworth, there is disclosed an outsole stitching machine provided with a knife acting automatically just before the end of the seam on a stitchdown shoe is reached to sever the welt from the supply at a point sufficiently in advance of the end of the welt first attached to the shoe, so that the final stitches of the

2

seam will conceal the ends of the welt and provide a smooth inconspicuous joint. While the machine of that patent is highly effective in producing a desirable result, under some circumstances it is preferable to utilize a welt severing and butting knife in an outside stitching machine for sewing stitchdown shoes, in which the operator of the machine may exercise greater discretion in matching and butting the ends of welt severed by the knife while at the same time inserting one or more stitches extending across the severed welt ends.

Accordingly, another object of the invention is to provide a relatively simple and effective welt severing and butting device for use in a stitchdown welt sewing machine which is capable of performing the same operations as those performed in the machine of the Ashworth patent without necessitating full automatic operation of the knife.

Other objects are to improve generally the operation of a stitchdown welt sewing machine by providing features of adjustments and improved arrangements for mounting the welt severing knife and its actuating mechanisms.

The present invention, accordingly, is illustrated in connection with a shoe machine having the usual fastening devices, a main welt guide mounted in the frame of the machine close to the operating devices for engagement with a shoe being operated upon, a supplemental welt guide through which the welt passes to the main welt guide and means carried by the supplemental welt guide for performing an auxiliary severing operation on the welt, in which machine means is provided movable with the supplemental welt guide for locating the position of the welt running to the main welt guide at which it is desired to perform the auxiliary operation. Where the auxiliary operation comprises butting the ends of the welt the supplementary welt guide and a severing knife are mounted on a carrier movable toward and from the main welt guide and the locating means comprises a feeler also mounted on the carrier. As herein-after described, the feeler comprises one member of a caliper acting on opposite surfaces along the sole margin of the shoe and in the preferred form the caliper is actuated by conveniently arranged manual means.

These and other features of the invention, as herein-after described and claimed will be apparent from the following detailed specification, taken in connection with the accompanying drawings, in which:

Fig. 1 is a detail view in elevation, looking from the right and toward the front of a lockstitch outsole shoe sewing machine and parts of a shoe operated upon being shown in section, which machine has been equipped with welt guides, a feeler and severing devices embodying the features of the present invention;

Fig. 2 is a sectional view taken along the line II—II of Fig. 1;

Fig. 3 is a detail view of certain parts in the machine shown in Fig. 1 illustrating the manner in which the feeler operates on a shoe sole;

Fig. 4 is a detail view looking at an angle from the left front of a machine equipped with the feeler and welt severing devices shown in Fig. 1;

Fig. 5 is a plan view of the parts shown in Fig. 1; and

Fig. 6 is a detail view in right side elevation of the machine with parts broken away and portions of a shoe shown in section.

The illustrated machine is generally similar to the lockstitch outsole shoe sewing machine disclosed in United States Letters Patent No. 473,870, granted April 26, 1892, in the name of French and Meyer, and No. 1,169,909 granted February 1, 1916, in the name Ashworth. The machine is intended primarily for fastening the outsole and welt of a Goodyear welt shoe but also it is employed

for fastening a narrow finish welt to the projecting marginal portions of the upper in the manufacture of a stitchdown shoe. The portions of a stitchdown shoe, illustrating their manner of presentation to the machine are indicated in Figs. 1 and 6. The shoe includes an outsole 2, the outflanged margin of a shoe upper 4, and a beaded stitchdown welt 6. The fastening or stitch forming devices of the machine comprise a curved hook needle 8, a curved awl 10 and a shuttle or loop taker 12, shown in Fig. 6. When operating upon a stitchdown shoe it is customary to present the shoe in inverted position, the shoe being engaged with and guided by a work support 14 which is provided with a main welt guide 15 in the form of an opening shaped to fit the welt and direct it in advance of the sewing point. The main welt guide directs the welt into the crease between the outflanged and bulging portions of the shoe upper 4 close to the operating point of the fastening devices and the thread, indicated at 16, is drawn through all of the shoe parts to form lockstitches fastening the parts permanently together.

In operating upon a stitchdown shoe in the manner outlined, the seam fastening the shoe parts together ordinarily is started along the inside of a shoe shank, a leading end 18 of the welt being first sewn to the shoe and the operation continued about the marginal portions of the shoe until the first end 18 of the welt already attached by stitches approaches the sewing point in the machine. The machine is then brought to rest, as illustrated in Fig. 1, and the welt in advance of the main welt guide is severed at a position at which the length remaining unattached to the shoe is equal to the distance between the sewing point and the first end 18 already attached. The machine is then restarted and the seam completed by inserting stitches overlapping the ends of welt which are brought into butting and matching engagement. In this way a smooth, inconspicuous joint is formed between the ends. Due to the position in which a stitchdown shoe is presented to an outsole sewing machine and to the arrangement of the main welt guide the welt advancing through the guide and the first end 18 already attached to the shoe are concealed from the view of the operator standing in a position normally assumed by him. Unless means are provided for accurately determining the position of the first end 18 already attached to the shoe, it is necessary for the operator to remove the shoe at least partially from the sewing point for this purpose before severing the welt leading from the main welt guide.

In the machine of the Ashworth United States Patent No. 2,388,245, a welt leading to the main welt guide of a shoe outsole sewing machine is severed automatically while the machine is running at a point determined from experience as the first stitches of the seam attaching the welt end 18 approach the sewing point, no interruption of the stitching being required. Due to slight variations in the position of the leading end of welt first attached to the shoe with respect to the first stitches which are visible to the operator, the actual leading end of the welt being concealed, some variation in appearance and character of the butted joint in the welt of a completed shoe may result. In accordance with the present invention an accurate joint in the welt running to the main welt guide 15 in the illustrated machine for sewing or otherwise fastening a welt to a stitchdown shoe may be formed without exercise of particular skill or prior experience in sewing stitchdown shoes and without removing the shoe from the sewing point in the machine.

To the ends noted above a horizontally shiftable supplemental welt guide mounted in the machine at a position more remote from the operating point than the main welt guide and fitted with a welt severing knife and locating means is engageable with the first end 18 of the welt already attached to the shoe to bring the supplemental guide to a predetermined relationship with the welt where it may be severed to the best advantage. In this way the

operator is no longer forced to depend on his judgment or prior experience. Similarly, other operations on the welt of an auxiliary nature, such as notching or beveling to fit particular surfaces of a shoe are controlled with equal facility.

In the preferred construction of this feature the supplemental welt guide together with the severing and locating means, in the form of feeder devices are mounted for easy detachment as a unit from the machine to facilitate servicing and to render the machine more versatile in the type of work for which it is capable of performing. For convenience in detachably mounting the supplemental welt guiding, severing and feeder devices the machine of the French and Meyer patent, more particularly as disclosed in United States Letters Patent No. 563,471, granted July 7, 1896, to the same inventors, has a dovetailed guide portion corresponding to that indicated at 20 in Fig. 1 of the present drawings, mounted on a rigid portion of the machine frame. In the machine of the invention the dovetail guide portion 20 has surrounding it a block 22 provided with a similarly shaped slot and a vertical spindle 24 carrying at its upper end a mounting for the supplemental welt guide and associated devices. When the block is applied to the dovetail portion 20 a wear plate 26 within its slot is clamped against the dovetail guide portion by a set screw 28 in the block to secure the block firmly in operating position in the machine.

The supplemental welt guide is in the form of a slotted block 30, the slot of which provides a passageway for the welt 6. As illustrated, the welt is of the storm type with a bead entering a groove along the lower surface of the slot in the guide block 30. To maintain a yielding pressure on the welt as it passes through the supplemental guide slot a pair of leaf springs 32 act in advance of the slot of the guide to engage the under surfaces of the main body on the welt and the projection of the bead, respectively. The leaf springs are secured to a cover 33 by clamp screws 34 passing through the springs and into the cover, the cover being secured to the guide block by screws 35. For limiting the upward movement of the springs the cover 33 has a flange extending across the path of the welt 6 in advance of the guide and a pin 36 secured in upstanding ears in the block 30 limits the upward movement of the belt beyond the slot in the block 30.

The welt severing knife, indicated at 38, is mounted for sliding movement toward and from the welt in the supplemental welt guide block 30 and is formed with beveled sides to provide a dovetail groove 40 (see Fig. 2) in the left hand inclined face of the block 30. For actuating the welt severing knife 38 its lower end is perforated to receive a screw 42 passing into threaded engagement with a clamp 44 having a central passage surrounding a sheath 46 of a Bowden wire 48, operated in a manner to be described. The Bowden wire 48 passes entirely through the clamp 44 and is attached at its uppermost end to the supplemental guide block 30. On the Bowden wire between the clamp 44 and the guide block 30 is disposed a compression spring 50 for retaining the knife 38 in its lowermost inactive position. When the knife is actuated upwardly it severs the welt 6 with a bevel cut against an edge 39 of the guide slot in the block 30, which acts as a cutting plate for the knife.

For shifting the supplemental welt guide block 30 horizontally it is secured to a carrier in the form of a bar 52 movable on the mounting provided by the spindle 24, the guide block 30 having a bore fitting the upper end of the carrier bar 52 and being secured thereto by a clamping bolt 54. The carrier bar 52 is formed with suitable bends and is pivotally mounted on a carrier supporting arm 56 rotatably mounted on the spindle 24 (see Fig. 5), the vertical position of the carrier supporting arm on the spindle being determined by a check nut 58 threaded on the central portion of the spindle below the carrier supporting arm. The axis about which the carrier bar pivots on the carrier supporting arm 56 is

parallel to the axis of the spindle 24 so that when the supporting arm rotates on the spindle the carrier rod 52 shifts in the direction of the welt running to the main welt guide in the work support 14, the welt 6 providing sufficient rigidity for guiding the shifting movement of the guide block 30 of the supplemental guide as it moves toward and from the main welt guide.

The pivotal mounting for the carrier rod 52 is formed by a short vertical stud 60 which passes through a split portion of the rod at its lower end and to which the rod is clamped by a screw 62 extending through its split portion. The ends of the stud 60 are indented and engage a pair of balls 64 entering similar indentations within a recess of the carrier supporting arm 56 and in the lower end of a screw 66, respectively, the screw being threaded in a flange portion of the carrier supporting arm. A check nut 68 engages the screw 66 and acts to secure it in proper relationship to the upper ball 64. As the carrier supporting arm swings on the spindle 24 the carrier bar moves the supplemental welt guide along the welt 6 toward and from the main welt guide and the stud 60 rotates on the balls 64 to enable the shifting movement of the supplemental guide to follow the welt 6.

The welt end feeler devices are mounted directly on the carrier bar 52 and comprise a caliper pivotally mounted on a substantially vertical rod 70 secured at its split lower end by a clamp screw 72 to the carrier bar. At the upper end of the rod 70 is an enlargement through which passes a horizontal shoulder bolt 74 clamped in position on the rod by a nut 76 (see Figs. 4 and 5). Rotatably mounted on an enlarged portion of the bolt 74 are a pair of blocks 78 and 80 provided with horizontal passages within which are located the welt end feeler in the form of an L-shaped shaft 82 and sole engaging caliper member in the form of an L-shaped rod 84, the shaft and rod being secured to the blocks 78 and 80 by draw bolts 86 passing through the respective blocks. The arrangement of the welt severing knife 38 within the guideway of the supplemental guide block 30 causes the knife to sever the welt with a bevel cut of approximately 45°. The left end of the shaft 82 therefore is formed with a welt end engaging surface 88 disposed at that angle to the horizontal. The left end of the rod 84 has rotatably mounted upon it a sole engaging roll 90 formed with a barrel-shaped outer surface to permit it to ride smoothly over any irregularity present on the sole 2.

During normal sewing operations the caliper comprising the feeler shaft 82 and the sole engaging rod 84 is inoperative and causes no interference with the movements of the shoe during sewing operations, the welt 6 in the supplemental welt guide holding it in a position out of the path of movement of the shoe as the sewing operation progresses. While sewing about the forepart and heel portions of a shoe the projection formed by the outflanged upper sole member and welt already attached thereto are clear of the space between the active ends of the shaft 82 and the rod 84. This is because the convex curvatures of the marginal edges on the shoe parts bring them out of the range of the feeler caliper. It is only while sewing about the inside shank of the shoe that the marginal portions of the shoe project into the space between the roll 90 and the feeler end of the shaft 82 as a result of the concave curvatures along these portions of the shoe edges. To prevent engagement of either caliper member with the shoe when the caliper is open the block 80 bears against the collar 91 releasably clamped to the rod 70.

When the leading end 18 of the welt first attached to a shoe reaches the position of Fig. 1 the sewing operations are temporarily terminated without severing the thread. While the machine is at rest, the feeler shaft and sole engaging rod are brought together against the shoe parts, as shown in Fig. 3 and the carrier supporting arm 56 is swung about the spindle 24 to shift the supple-

mental welt guide and caliper members toward and from the main welt guide in the work support until the welt end engaging surface 88 on the feeler is brought into definite contact with the first end of welt 18 attached to the shoe. Proper stopping position of the machine may be ascertained roughly by the approach of the stitches first inserted which are readily visible to the operator of the machine. Engagement of the feeler surface 88 with the welt end 18 then provides means for accurate location of the supplemental welt guide within which is slidably mounted the knife 38. After being properly located the knife 38 is actuated to form a bevel cut end, butting and matching exactly the first end 18. After restarting the machine stitches are then continued across the butted ends of the welt on the shoe completed in the usual manner.

For actuating the caliper to open and close against the projecting marginal portions of a shoe, for shifting the carrier to move the supplemental welt guide and knife 20 along the welt running to the main welt guide and for actuating the knife to sever the welt a single manually operated member is provided. Thus, it is possible for the operator of the machine to support a shoe with one hand and to locate the end 18 of welt, already attached to a shoe, shifting the knife carrier to the proper location to butt and match the bevel at the end 18 of welt while grasping the single manually operated member with the other hand. The operation of severing the welt is executed without shifting the operator's grasp on the shoe or readjusting his grip on the operated member.

The single manually operated member for actuating the feeler, caliper members and knife is pivotally mounted for movement upon the carrier supporting arm 56 for relative movement both horizontally along the welt and vertically toward and from the marginal portions of the shoe. For actuating the caliper to engage the projecting marginal portions of the shoe with an opening and closing motion the manually operated member is rotated in a counterclockwise direction about an axis passing through itself so as to be accomplished readily by rotation of the operator's wrist.

The pivotal mounting for the manually operated member on the carrier supporting arm 56 is similar to that provided for the carrier rod 52 on the supporting arm 56 and consists of a pair of balls 92 mounted in an indentation of a flange on the carrier supporting arm and in the lower end of a screw 94, respectively, the screw 94 passing through a flange on the supporting arm 56 directly above the one which receives the lower ball 92. The balls 92 also enter indentations in a block 96 on which is supported a handle arm 98 projecting forwardly and toward the right of the machine. The forward end of the arm 98 has a horizontal bearing through which passes loosely a handle shaft 100. At the forward end 55 of the handle shaft is mounted the manually operated member in the form of a grip shaped handle knob 102 (see Fig. 1), the shaft being perforated to receive a pin 104 passing through it and the knob 102.

To shift the supplemental welt guide with the knife 60 and feeler caliper toward and from the main welt guide in the work support 14 the manually operated knob 102 is moved horizontally in the direction corresponding to that in which the supplemental welt guide and caliper are to be shifted. To prevent overrunning of the feeler surface 88 on the shaft 82 past the first end 18 of the welt on a shoe the block 96 forms a pivotal connection between the arm 98 and the carrier supporting arm 56 and is yieldingly connected to the supporting arm through a torsion spring 106 surrounding the upper ball 92, with one end engaged with the block 96 and the other with the supporting arm 56. The spring 106 is so stressed that as the knob 102 is moved toward the right it will yield as soon as the surface 88 engages the end 18 of welt first attached to a shoe. To limit the pivotal movement 70 of the handle knob toward the left with respect to the

carrier supporting arm the block 96 engages an abutment 108 (see Fig. 5) on the arm.

For opening and closing the caliper members on the surfaces along the marginal projecting sole and other portions of the shoe parts the handle knob 102 is rotated with the shaft 104, the axis of which passes through the knob itself. The shaft 100 is formed with a right hand helical groove 110 into which fits a roll 112 rotatably mounted on a reduced end of a shoulder screw 114, the enlarged portion of which is threaded into a boss on the handle arm 98. Beyond the bearing for the shaft 100 in the arm 98 is an enlarged opening within which is located a compression spring 116 surrounding the shaft 100. The spring 116 is compressed between the inner end of the enlargement in the opening and a block 118 loosely surrounding the shaft 100, the block 118 having a section of reduced width projecting downwardly through a slot 99 along the lower surface of the handle arm 98. To retain the block 118 in position on the shaft 100 against the compression of the spring 116 the inner end of the shaft has secured to it a collar 120. Connected with the portion of reduced width on the block 118 is the forward end of a Bowden wire 122 passing through a sheath 124 secured by a clamp screw 126 in a lug on the handle arm 98. The other end of the sheath 124 has connected to it a sleeve 127 through which also the Bowden wire 122 passes and continues through enlarged heads on a pair of pins 128 rotatably mounted in the caliper blocks 78 and 80. The caliper blocks are normally separated by a spring 130 compressed between the heads on the pins 128 and the caliper members are closed on the shoe parts yieldingly against the action on a spring 132 surrounding the Bowden wire 122 between the lowermost pin 128 and the sleeve 127 to limit the pressure of the caliper members on the shoe parts. The arrangement is such that when the knob 102 is rotated the caliper members open or close on the marginal portions of a shoe so that as the carrier bar 52 is shifted toward the right the surface 88 on the shaft 82 will be brought against the end 18 of the welt.

To connect the manually operated knob 102 for operation of the welt severing knife 38 the handle arm 98 is mounted for vertical pivotal movement on the block 96. For this purpose the block 96 has threaded into it a shoulder screw 134 passing loosely through the rearward portion of the handle arm. The handle arm is held raised normally during sewing operations by a spring 136 stretched between a pin 137 on the handle arm and a screw 138 threaded into a lug on the supporting arm 56. The spring 136 holds the handle arm in raised position determined by the engagement of a pin 140 (see Fig. 4) on the handle arm with a vertical edge surface on the block 96.

The connections between the handle arm and the welt severing knife 38 include the Bowden wire 48 secured in a passage intersecting the threaded portion of the lug on the supporting arm 56 into which the screw 138 passes, the screw 138 acting to clamp the Bowden wire 48 in place. The Bowden wire 48 also passes through a square head on a pin 142 to which is fixed the sheath 46 for the wire 48. The pin 142 is rotatably mounted in the handle arm 98 and the sheath 46 extends into the clamp 44 on the welt severing knife as hereinbefore described. Downward movement of the handle knob acts through the connections thus described to slide the sheath 46 along the Bowden wire 48 and to raise the knife 38 into engagement with the welt.

To prepare the machine for operation upon a shoe the welt is advanced manually through the supplemental and main guides to bring the end across the sewing point to a position where the awl will pierce it during its first forward movement. The sewing operation being started it is continued entirely about the projecting marginal portions of a shoe until the stitches first inserted become visible. After stopping the machine the manually oper-

ated knob is moved in the proper manner to caliper the leading end 18 of the welt first attached to the shoe and to sever the welt in the position thus determined. The parts are properly adjusted to cause the severed end of the welt attached to the shoe to match exactly with and to butt against the first end 18 of the welt when the sewing operation is resumed so that after the stitches have been carried across the butted ends a neat and well concealed joint will be completed.

10 The machine equipped with the supplemental welt guide, caliper and severing knife may conveniently be operated with relatively little experience if the machine is brought to rest while operating the handle knob 102. To sever a stichdown welt the operation of the knob 15 also may be effected, without deviating from the scope of the invention, immediately prior to the completion of a sewing operation without stopping the sewing operations, it being possible for an experienced operator to control the feeler and severing devices while the machine 20 is running. Also, the actuation of the knife may be performed in a manner similar to that disclosed in the Ashworth patent automatically whenever the feeler surface 88 is engaged by the end of a welt attached to a shoe. Under these conditions the movements of the handle knob 102 25 will shift the carrier for the caliper to the right to bring the feeler surface against the welt end of a shoe and as the shoe is fed the feeler member will be moved toward the left with a shoe while the knife is being actuated.

The nature and scope of the invention having been 30 indicated and a particular embodiment having been described, what is claimed is:

1. A shoe machine having a main frame, fastening devices in the frame, a main welt guide mounted in the frame close to the point of operation of the fastening 35 devices for engagement with a shoe being operated upon by the fastening devices, a supplemental welt guide located along the path of the welt leading to the main welt guide more remote from the operating point than the main welt guide, knife means carried by the supplemental welt 40 guide for performing a severing operation on the welt before it enters the main welt guide and a carrier on which the supplemental welt guide is secured mounted on the main frame for shifting movement toward and from the main welt guide, in combination with feeler means 45 mounted on the supplemental welt guide carrier and engageable with the first end of welt already attached to a shoe for locating the position along the welt running to the main welt guide at which the severing operation is performed.

2. A shoe sewing machine having a main frame, stitch forming devices in the frame, a main welt guide mounted in the frame close to the point of operation of the stitch-forming devices for engagement with a shoe being operated upon by the stitch forming devices, a horizontally 55 shiftable supplemental welt guide located along the path of the welt leading to the main welt guide more remote from the operating point than the main welt guide, a knife carried by the supplemental welt guide for severing the welt passing therethrough before it enters the main 60 welt guide and a carrier on which the supplemental welt guide is secured mounted on the main frame for horizontal shifting movement toward and from the main welt guide, in combination with a feeler mounted on the supplemental welt guide carrier and movable with the carrier along a shoe being operated upon to bring the knife into predetermined relationship with the end of the 65 welt already attached to the shoe.

3. A shoe sewing machine having a main frame, stitch forming devices in the frame, a main welt guide mounted 70 in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and 75

a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt.

4. A shoe sewing machine having a main frame, stitch forming devices in the frame, a main welt guide mounted in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt, and means for opening and closing the caliper to bring it into operative relationship to the margin of a shoe.

5. A shoe sewing machine having a main frame, stitch forming devices in the frame, a main welt guide mounted in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt, and a single manually operated member for opening and closing the caliper on the sole margin of the shoe and for shifting the carrier to move the supplemental welt guide and knife along the welt running to the main welt guide.

6. A shoe sewing machine having a main frame, stitch forming devices in the frame, a main welt guide mounted in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt, a single manually operated member for opening and closing the caliper on the sole margin of the shoe and for shifting the carrier to move the supplemental welt guide and knife along the welt running to the main welt guide, and connections between the manually operated member and the knife for actuating it to sever the welt.

7. A shoe sewing machine having a main frame, stitch forming devices in the frame, a main welt guide mounted in the frame for engagement with a shoe being operated

upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt, a shaft on the carrier, and a manually operated knob mounted on the shaft with the axis of the shaft passing through the knob for opening and closing the caliper on the sole margin of the shoe through rotation of the knob about the shaft axis.

8. A shoe sewing machine having a main frame, stitch forming devices in the frame, a main welt guide mounted in the frame for engagement with a shoe being operated upon by the stitch forming devices, a horizontal shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a caliper acting on opposite surfaces along the sole margin of a shoe and comprising a feeler mounted on the supplemental welt guide carrier to locate the position of the end of the welt already attached to the shoe at which the knife may be actuated to form a matching end on the welt, a shaft on the carrier, a manually operated knob mounted on the shaft with the axis of the shaft passing through the knob for opening and closing the caliper on the sole margin of the shoe through rotation of the knob about the shaft axis, and yielding connections between the shaft and the caliper to limit the pressure of the feeler on the shoe parts.

9. A shoe sewing machine having a main frame, stitch forming devices in the frame, a main welt guide mounted in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in combination with a feeler mounted on the supplemental welt guide carrier and movable with the carrier along a shoe being operated upon to engage the end of the welt already attached to the shoe and to bring the knife into predetermined relationship with said welt end, a handle knob mounted on the carrier and movable therewith to shift the carrier in the direction of movement of the knob, and a yielding connection between the knob and the carrier to prevent the feeler from overrunning the end of the welt on the shoe.

10. A shoe sewing machine having a main frame, stitch forming devices in the frame, a main welt guide mounted in the frame for engagement with a shoe being operated upon by the stitch forming devices, a horizontally shiftable supplemental welt guide located along the path of the welt leading to the main welt guide, a knife carried by the supplemental welt guide for severing the welt passing therethrough before it enters the main welt guide and a carrier on which the supplemental welt guide is secured mounted on the main frame for horizontal shifting movement toward and from the main welt guide, in

combination with a feeler mounted on the supplemental welt guide carrier and movable with the carrier along a shoe being operated upon to bring the knife into predetermined relationship with the end of the welt already attached to the shoe, and a handle arm mounted for vertical pivotal movement on the carrier for actuating the knife against the welt.
